DESIGN FOR A LAMP SHIELD

Clyde D. McCann, Des Moines, Iowa

Application January 15, 1941, Serial No. 98,093

Term of patent 14 years

To all whom it may concern:

Be it known that I, Clyde D. McCann, a citizen of the United States and resident of Des Moines, Polk County, Iowa, have invented a new, original, and ornamental Design for a Lamp Shield, of which the following is a specification, reference being had to the accompanying drawing, forming a part thereof.

Fig. 1 is a front elevational view of a lamp shield showing my new design.

Fig. 2 is a side elevational view thereof.

Fig. 3 is an enlarged bottom plan view of the same.

I claim:

The ornamental design for a lamp shield, substantially as shown.

CLYDE D. McCANN.
